ROD HANGER

Alan M. Roberts, Long Beach, and Jesse H. Smith,
Lynwood, Calif.

Application July 22, 1940, Serial No. 346,822

8 Claims. (Cl. 24—249)

This invention relates to a rod hanger whereby sucker rods, pipe or tubing may be suspended in a derrick or rack while the said sucker rods, pipe or tubing are awaiting use in a well.

The purpose of our rod hanger is to hold the lengths of pump, rod or tubing off of the derrick floor as the rods or tubing are pulled out of the hole. Thus, the rods or tubing are not bent or injured while awaiting use in the well.

An object of our invention is to provide a novel rod hanger which is self-tightening, and which frictionally engages the rod or pipe to effectively hold the same.

Still another object is to provide a novel rod hanger of the character stated, which is so hinged that it can be quickly and easily assembled or disassembled about the rod or pipe.

Still another object is to provide a novel rod hanger of the character stated, which is simple in construction, effective in use, and inexpensive to manufacture.

Other objects, advantages and features of invention may appear from the accompanying drawing, the subjoined detailed description, and the appended claims.

In the drawing:

Figure 1 is a side elevation of our rod hanger in position on a length of pipe.

Figure 2 is a top plan view of our rod hanger with the pipe shown in section.

Figure 3 is a perspective view of our rod hanger.

Referring more particularly to the drawing, our rod hanger consists of a pair of arcuate complementary jaws 1, 2. These jaws are hingedly connected together as shown at 3. The jaws 1 and 2 encircle the pipe 4 or rods or the like, as shown in Figures 1 and 2, and the inside of the jaws are preferably smooth so that the exterior of the pipe, rods or the like will not be scarred.

The jaws 1 and 2 are each provided with outwardly extending plates 5 and 6, which are integrally formed with the jaws. The plate 5 is provided with a horizontal arm 7 at the bottom, which is integrally formed with the plate and which extends under the plate 6, as shown in Figures 1 and 3. A clamping finger 8 is hingedly attached to the outer end of the arm 7, as shown at 9. The upper end of the finger 8 is bent outwardly as shown at 10, and a cable 11 is attached to this extension for the purpose of suspending the rod hanger and the rods in a rack or in the derrick. A button or lug 12 on the inside of the finger 8 bears against the plate 6 and when the

holder is suspended in a rack or in the derrick, the weight of the holder and the pipe or rods gripped therein will press the clamping finger tightly against the plate 6, thus pressing this plate towards the plate 5, and compressing the jaws 1 and 2 around the pipe or rods. By varying the length of the extension 10 or the finger 8, the amount of force compressing the jaws 1 and 2 around the pipe or rods can be varied.

Having described our invention, we claim:

1. A rod hanger comprising a pair of arcuate jaws, means hingedly connecting the jaws, clamp means engaging one of said jaws whereby said jaw is pressed towards the other jaw, and suspending means attached to said clamp means.

2. A rod hanger comprising a pair of complementary arcuate jaws, said jaws being hingedly connected, a clamping finger hingedly connected to one of the jaws, said clamping finger engaging the other jaw, and suspending means attached to said finger.

3. A rod hanger comprising a pair of arcuate complementary jaws, means hingedly connecting the jaws together, a clamp finger hingedly connected to one of the jaws, said clamp finger engaging the other jaw whereby the jaws are pressed together around the rod, an extension on the clamp finger, and suspending means attached to said extension.

30 4. A rod hanger comprising a pair of arcuate complementary jaws, means hingedly connecting the jaws together, a plate extending outwardly from each of the jaws, said plates being spaced, a clamping finger hingedly connected to one of the plates, said clamping finger engaging the other plate, an extension on the clamping finger, and suspending means attached to said extension.

40 5. A rod hanger comprising a pair of arcuate complementary jaws, means hingedly connecting the jaws together, a plate extending outwardly from each of the jaws, said plates being spaced, a clamping finger hingedly connected to one of the plates, said clamping finger engaging the other plate, an extension on the clamping finger, and suspending means attached to said extension, and a lug on the clamping finger engaging one of said plates.

45 6. A rod hanger comprising a pair of complementary arcuate jaws, said jaws being hingedly connected, a clamping finger hingedly connected to the lower end of one of the jaws, said clamping finger extending to the other jaw and projecting vertically adjacent said jaw, said clamping finger engaging the other jaw in the latched

position of the hanger and suspending means attached to said clamping finger.

7. A rod hanger comprising a pair of arcuate complementary jaws, means hingedly connecting the jaws together, a clamp finger hingedly connected to the lower end of one of the jaws, said clamp finger extending vertically adjacent the other jaw and engaging said other jaw in the clamped position of the hanger, a horizontal extension on the upper end of the clamp finger, and suspending means attached to said extension.

8. A rod hanger comprising a pair of arcuate

complementary jaws, means hingedly connecting the jaws together, a plate extending outwardly from each of the jaws, said plates being spaced, a clamping finger hingedly connected to the lower end of one of the plates, said clamping finger extending vertically adjacent the other plate and engageable with said other plate in the latched position of the hanger, an extension on the upper end of said clamping finger, and suspending means attached to said extension.
